HANDKERCHIEF

Renzo Bemporad, New York, N. Y.

Application May 5, 1955, Serial No. 35,814

Term of patent 3½ years

(Cl. D3—12)

The figure is a plan view of a handkerchief showing my new design, both faces being identical.

My design comprises a handkerchief having narrow light stripes upon a dark ground and a wide light border on two sides edged in the ground color; the two opposite corners of the border being chamfered, and a line of the ground color parallel to the chamfered corners divides the border, as shown.

I claim:

The ornamental design for a handkerchief, substantially as shown and described.
